FIG. 2.

FIG. 3.

UNITED STATES PATENT OFFICE.

HARRY F. HOWELL, OF CLEVELAND, OHIO.

ELECTRIC ELEVATOR.

1,373,132.

Specification of Letters Patent. Patented Mar. 29, 1921.

Application filed April 8, 1920. Serial No. 372,113.

To all whom it may concern:

Be it known that I, HARRY F. HOWELL, a citizen of the United States, residing at Cleveland, in the county of Cuyahoga and State of Ohio, have invented certain new and useful Improvements in Electric Elevators, of which the following is a specification.

This invention pertains to an improvement in electric elevators which functions to safeguard the operations of such elevators, to keep check on their movements, and to promote their control. It frequently happens that such elevators become stalled at the top or bottom of the elevator shaft, due to an accident or the negligence or inexperience of the operator and because of the use of safety appliances which are installed to meet laws and ordinances governing and regulating the operation of such elevators. That is to say, these appliances are designed to slacken the speed and to stop the elevator automatically as it reaches the extreme bottom or top of the shaft, and if the car passes a given distance beyond the top and bottom landings the electric current is automatically switched off to prevent the car from proceeding farther in that direction. This leaves the car without electric current or power, and it is stalled in the shaft with its passengers.

Assuming that this has occurred at one end of the shaft, the operator within the car is unable to restore or switch on electric current to operate the car without outside assistance, particularly as the electric current required to operate the car is cut off at its source by a magnetic switch on the control board which is usually located at a very remote and distant point. Generally this control board is at the top of the elevator shaft and in order to place the car in service it is necessary for someone outside of the car to visit the control board and operate the magnetic switch manually to reestablish the electric working circuit and then the operator in the car must be notified. It is not an uncommon experience, where many elevators are used, to have this malfunction in operations occur many times in a day, because the operators become careless or through inexperience permit the car to pass beyond its normal working limits, and the cars are placed out of commission for such periods of time as it takes to visit the control board and to reestablish the

electric circuit. In the event of fire or a panic there is increasing danger of cars becoming overloaded and the operator becoming excited and the cars becoming stalled at the bottom or top of the shaft beyond the landings, and under those conditions the passengers would be trapped and entirely dependent upon outside aid to release them by reestablishing the broken circuit at the control board at the top of the shaft or in the top floor or super-structure where this device and other operating apparatus is usually operated.

With the present invention, whenever the car becomes stalled and the magnetic switch deenergized a signal light is illuminated at a central or given station. An authorized person or supervisor at this station may then instantly close the distant magnetic switch and hold it in that position to provide a working circuit and power for the car until the operator in the car has shifted the car back to its normal place of operations. The working circuit established by the supervisor is a temporary one and in creating it a signal light is illuminated in the car, or within the range of vision of the operator, to apprise him that he may, without delay, move the car back to its normal place of operations. When the car moves back to place the signal light at the station is extinguished automatically and the supervisor is thereby notified that proper working conditions have been reestablished. He then cuts off the temporary working circuit and the system is in its regular order to permit a repetition of such operations if the need arises.

In the drawings accompanying this application, Figure 1 is a diagram of a complete electrical operating system for an electric elevator, including my improvement, and showing the position of the parts under normal working conditions. Figs. 2 and 3 are similar views, but contracted to my improvement and showing in Fig. 2 the position of the parts when the car is stalled and cut off from power, and in Fig. 3 when still down but temporarily provided with power by the supervisor.

Referring to Fig. 1, it must be understood that the electric elevator system shown therein is in the main a system now in general use. However, a brief description thereof is necessary for a clearer understanding of my improvement. Thus, the system com-

prises an electric motor A for raising and lowering the elevator or car B at varying speeds. Starting and stopping and the speed is regulated by a controller C in the hands 5 of an operator within the car. Motor A and the cable winding mechanism (not shown) together with the switch board having a set of magnetic switches D, E, F and G, are located as a rule in a pent-house on 10 the roof of the building above the elevator shafts, and separate sets of pivoted switches H, I and J are placed within the upper and lower ends of each shaft where each switch will be engaged successively by the car and thrown open to cut off the electric current, 15 first, at the fast speed switch G, secondly, at switch E or F depending upon whether the car is going up or coming down, and thirdly, at the main magnetic switch D 20 which controls the current at the leads or source of supply. The safety or breaker switches J in the shaft are not opened except when the car passes a given distance beyond the landing, and failure of the car to 25 stop at the landing may be caused by an overloaded car, or the operator may be at fault. When this mishap occurs, as shown in Fig. 2, the breaker switch J at the bottom of the shaft is opened and the main magnetic switch D deenergized and the electric current cut off over circuit 2 which connects all these parts together, including a knife switch K and controller C in the car. Under 30 these conditions the car is stalled below the 35 landing in the well or bottom of the shaft and the operator is unable to reestablish an operating circuit or to move the car upward without aid from someone outside the car.

However, with my improvement the mishap may be instantly apprehended and corrected at a distant point, preferably a central station where a supervisor or attendant may keep check on all the elevators in the building and restore working conditions 40 without leaving his post. To that end I provide an auxiliary switch L in the shaft which is engaged and closed by a shoe on the car at the same time that breaker switch J is engaged and opened, thereby closing an 45 electric lighting circuit 3 having an electric lamp 4 located at the supervisor's station. This lamp remains illuminated as long as the car is stalled, but the supervisor is enabled to instantly correct this condition by 50 closing a switch 5 at this station, providing a lock switch 6 in series with switch 5 is also closed. These two switches are in circuits 7 and 2 which begins and ends at the 55 supply leads and includes the coil 8 of the main magnetic switch D, a speed governor switch 9, and the knife switch K which connects with controller C in the car. Consequently, when the switches 5 and 6 are 60 closed by the supervisor the magnetic switch 65 is energized and the main operating circuits

of the system restored to use, and the operator in the car may then raise the car from its stalled position. To avoid delays and accidents I also extend circuit 7 to the car or a place opposite the car and connect a 70 lamp 10 in series with the switches and other appliances in that circuit, whereby when the supervisor closes switches 5 and 6 to energize and close the main magnetic switch D he will at the same time cause lamp 10 to 75 be illuminated as a signal to the operator in the car that the electric power is again on and that the controller C may be manipulated to raise the car out of its stalled position. When the operator responds to this 80 signal and the car moves far enough to disengage switch L in the shaft the lamp 4 at the supervisor's station is extinguished and at about the same instant the breaker switch J is also released or disengaged by the car 85 and as it closes under gravity or spring control the main or original working circuit 2 is reestablished so that the car may be operated as under normal working conditions. Consequently, when lamp 4 is extinguished 90 the supervisor is made aware of the restoration of the car to its normal working place in the shaft and he thereupon opens switch 5, or both switches 5 and 6, which act breaks circuit 7, extinguishes lamp 10 in the car, 95 but does not deenergize coil 8 of the main magnetic switch D for the reason that this coil has in the interim been placed in connection with the source of supply of electric current through the closing of breaker 100 switch J.

The supervisor's switch 5 is preferably one of a self-opening type which is adapted to require the constant attention of the supervisor to hold it in a closed position and so that when it is released it will automatically open circuit 7. Switch 6, on the other hand, is of the lock-type requiring a key to place it in an open or closed position, whereby when said switch 6 is open it will not avail any one to operate switch 5. When the supervisor is at his position switch 6 may be locked in a closed position, but if absent he may open switch 6 and no one without the proper key will be able to make effective 110 use of switch 5 and avoid being checked and apprehended in the act of stalling a car. In this connection, it should be understood that in some large department stores there are as many as twenty-five or thirty electric 115 elevators and the operators or employees frequently use such elevators without permission and purposely or carelessly stall them, and it is very desirable that a check be kept on the use of the cars to avoid delays and accidents. It is also desirable to prevent the operations of the cars by unauthorized persons at night and during such periods of time as the regular operators are not at their station, and to that end I also 120 125 130

provide a lock switch 12 at the supervisor's station which is connected in series with the other switches and appliances in circuit 2 so that this circuit may be broken and the 5 switch locked in an open position to prevent all persons other than an authorized person with a key to place the main working circuits for a given car in an operative condition. It should be understood that opening 10 of night lock switch 12 deenergizes the main magnetic switch D and that the closing of said switch energizes said magnetic switch and establishes the main working circuits for the motor and other electric apparatus used in operating the car.

What I claim is:

1. In an electrical elevator, a main electric circuit and means therein adapted to automatically cut off the power current for 20 the elevator when the elevator approaches one end of the elevator shaft, and an additional electric circuit having means therein adapted to effect a temporary restoration of flow of current over said main circuit until a retrograde movement of the elevator has been obtained.

2. In an electrical elevator, an electric operating circuit for the elevator, means adapted to render said circuit inoperative 30 during movement of the elevator in a given direction, means adapted to signal the inoperative condition of the elevator and circuit, and an electric circuit having means therein adapted to reestablish momentary 35 operative conditions over said first circuit.

3. In an electrical elevator, an electric operating circuit for the elevator, means adapted to render said circuit inoperative during movement of the elevator in a given 40 direction, means adapted to signal the inoperative condition of the elevator and circuit, an electric circuit having means therein adapted to reestablish momentary operative conditions over said first circuit, and 45 means adapted to signal the operator of the elevator coincidentally with said reestablishment of operative conditions.

4. In an electrical elevator, an electric power circuit, a magnetic switch to open 50 and close said circuit, a breaker switch adapted to open said circuit and deenergize

said magnet switch upon a movement of the elevator beyond predetermined bounds, and a supervisor's electric circuit and switch adapted to supply current to said magnetic switch while the elevators are beyond bounds and without power to return. 55

5. In an electrical elevator, a power circuit for the elevator, an automatic device operably dependent upon the movement of the elevator adapted to open said power circuit, and means adapted to close said power circuit when opened by said device, comprising a manually-operated switch and a lock switch connected in series. 60 65

6. In an electrical elevator, a power circuit for the elevator, a safety switch in said circuit adapted to be opened automatically by the movement of the elevator, a signaling circuit having a self-opening switch 70 adapted to be closed by the movement of the elevator, a switch and electric circuit adapted to effect a temporary closing of the power circuit from a fixed station, and signaling means in said last circuit adapted to 75 apprise the operator in the elevator when the power circuit has been reestablished.

7. In an electrical elevator, a main electric circuit having a safety switch adapted to be opened by the movement of the elevator, and a separate electric circuit having a momentary switch and a lock switch adapted to close the main electric circuit during the interim the safety switch is open. 80

8. In an electrical elevator, a main electric circuit having a safety switch adapted to be operated by the movement of the elevator, a lock switch for said circuit placed at a station, and a supplemental electric circuit having a momentary switch at said station adapted to close said main electric circuit while the safety switch is open. 85 90

9. In an electrical elevator, a main electric circuit having a magnetic switch and a safety switch and a lock switch therein, 95 and an additional electric circuit adapted to energize said magnetic switch having a momentary switch and a lock switch therein.

Signed at Cleveland, in the county of Cuyahoga, and State of Ohio, this 3rd day of April, 1920. 100

HARRY F. HOWELL.
